UNITED STATES PATENT OFFICE.

JOHN DEAN, OF RACINE, WISCONSIN, ASSIGNOR TO JOHN DEAN MANUFACTURING COMPANY, OF RACINE, WISCONSIN, A CORPORATION OF WISCONSIN.

MATCH-FLARE.

1,001,191.

Specification of Letters Patent. Patented Aug. 22, 1911.

Application filed April 28, 1910. Serial No. 558,310.

To all whom it may concern:

Be it known that I, JOHN DEAN, a citizen of the United States, residing at Racine, Racine county, Wisconsin, have invented 5 certain new and useful Improvements in Match-Flares; and I do hereby declare the following to be a full, clear, and exact description of the invention, such as will enable others skilled in the art to which it 10 appertains to make and use the same.

This invention relates to certain improvements in match flares, and the like; and the objects and nature of my invention will be readily understood by those skilled in the 15 art in the light of the following explanation of the accompanying drawings illustrating what I now consider my preferred embodiments from among other formations within the spirit and scope of my invention.

20 The invention consists in certain features in construction and in formations and arrangements as more fully and particularly set forth hereinafter.

Referring to the accompanying drawings;—Figure 1, is a perspective view of a tube constructed in accordance with my invention and forming a multiplicity of separable match flares, one flare being shown partially broken or separated from said 30 tube, each flare being shown bearing advertising matter on the exterior surface thereof. Figs. 2 and 3, are perspective views from opposite sides of a folded sheet or blank from which a tube, Fig. 1, can be 35 formed by rolling and pasting. Fig. 4, is a perspective view of a tube constructed in accordance with my invention and adapted to be cut into flares of the desired length, this tube not being formed with the lines of 40 weakness present in the tube of Fig. 1. Fig. 5, is a perspective view of a match having a flare of my invention affixed thereon. Fig. 6, is a perspective view of a match flare enlarged. Fig. 7, shows a flare in longitudinal section and confined on a match and lapping and adhering to the head thereof.

The flare of my invention is composed of a usually flexible or compressible thin walled tube or sheet having an initial igniting end wall or edge and being formed by a rolled and pasted sheet of pulp or paper material carrying or impregnated with a substance to accelerate oxidation or combustion preferably without the production or

presence of an extensive flame. These flares 55 can be made separately or individually, each being formed by rolling a sheet of the width of a single flare, or elongated tubes can be formed in length equal to the length of a number of flares so that the tubes can thereafter be cut or broken into short lengths to form a multiplicity of flares. These elongated tubes can be formed with spaced lines of weakness or separation to render the same 60 readily separable or breakable into the individual flares; or the tubes can be formed as shown by Fig. 4, without these lines of 65 weakness and adapted to be cut into the desired lengths to form flares, with or without inscriptions or advertising matter on the 70 exterior surfaces thereof.

The tubes of a length to form the multiplicity of flares can be sold as attachable match flares to be carried on the person and supply flares for attachment to matches 75 when needed for use as such. If desired, the flares can be attached to matches in the process of preparing the matches for the market so the matches can be furnished to the trade with the flares of my invention applied thereto, as shown by Fig. 5. In the process of preparing matches for the market these flares of my invention can be slipped onto the match stems, by hand or machinery, with the flares partially overlapping the match heads, each match head being moist when the flare is applied thereto or having been previously softened as by the application of moisture thereto so that the flare will be cemented and secured to 90 the match by the head when dried and thus in effect form a permanent part of the match, or the flares might be formed and secured on the matches by rolling the sheets directly on the match stems. The walls of 95 the flares are preferably comparatively thin or flexible so that the flares can be readily slipped on match stems of varying sizes and cross sectional formations with the flare conforming thereto.

100 The construction and formation of the flare is such that under combustion it contracts or shrinks and thus binds on or grips the match stem and remains thereon as a live coal and does not slide down the stem onto 105 the fingers or drop from the stem as a menace to property. The flare is composed of such material and carries such oxidation ac-

celerating substance as to produce under combustion a red hot or incandescent body without objectionable flame and which will maintain its tobacco or acetylene gas igniting qualities for a desirable length of time. The wind proof or flare matches now on the market, must be used for igniting purposes while flaming inasmuch as the match is dead on the passing of the flame, 5 a live coal is not left that can be utilized for igniting purposes, and while this flaming match of commerce is thus blazing a strong pungent or acrid odor is given off which is destructive to the flavor of tobacco and yet 10 tobacco can be ignited therefrom only when this match is thus flaming or blazing. My flare avoids these objections and is not only wind proof in the sense of the fire match of commerce, but produces an incandescent coal 15 20 which can be utilized for a considerable length of time for igniting purposes without giving off objectionable odors or flame, although all features of my invention are not restricted to the production of an incandescent coal for igniting purposes, but this does 25 constitute one feature of my invention.

At present I prefer to form the flares from tissue like sheets of paper or fibrous pulp or equivalent combustible material 30 rolled in the direction of their lengths in overlying convolutions and pasted and rendered inflammable to accelerate combustion by application of suitable material before or after rolling the sheets. I usually employ 35 for this purpose a suitable solution of potassium nitrate with which the sheets are impregnated and then dried before rolling although I do not wish to so limit my invention.

40 Where a series of detachably jointed flares or sheaths is to be formed, I take an elongated thin sheet 1, which in width is equal to the combined lengths of the sheaths to be formed thereby, and which is preferably formed throughout its length with parallel lines of weakness or separation 2 (for instance rows of perforations or score lines) spaced apart, usually equally, a distance equal to the length of a completed sheath. 45 At the outer surface of one end (that is at the portion of the sheet which forms the secured exterior surfaces of the completed sheaths) said sheet can be provided with visible intelligible characterizations 3, of any form or 50 design to convey meaning to the human mind through the eye. The characterizations 3, whether letters, symbols or other representations are usually of an advertising character, and the lines of weakness 2, divide the 55 end of the sheet into series of similar advertising spaces, each space receiving or containing advertising matter 3, complete in itself to be displayed on the outer surface of a sheath, so that the sheet will at one end

have a series of groups of advertising characterizations or representations 3. This highly inflammable sheet is then transversely doubled or folded on itself, say on the line 4, to form two superimposed plies, the outermost ply, which is provided with 65 the advertising matter 3, being of greater length than the other or inner ply so as to form the end 5, of the outer ply (bearing the advertising matter) projecting at least a distance equal to the length of each advertising space, that is a distance at least about equal to the circumference of a completed sheath to form the secured outer advertising surface of the sheath. The inner surface of this projecting end 5, (bearing the advertising matter on its outer surface) is then coated or otherwise provided with a suitable adhesive, preferably an adhesive that will not retard combustion. For instance, for this purpose, I can employ a mucilagenous substance dissolved in a potassium nitrate solution. A straight wire or the like, of the required small diameter is then laid in and transversely of the folded sheet, and then by contact with a rapidly rotating surface 80 85 while held in a suitable former or holder, the sheet is wound or rolled on the wire into the sheath or roll form and secured in such form by the adhesive on the projecting end 5, which forms and constitutes the exposed 90 outer surface of the roll.

The folded sheet is rolled on itself in the direction of its length into comparatively loosely and directly overlying convolutions, each convolution being composed of two 100 plies of the sheet, excepting one or more outer convolutions formed by the projecting end 5, and hence being of single ply. The folded sheet is so folded that its short ply forms the inner ply of each convolution and 105 the surface surrounding the center opening of the completed roll, and the free end extremity of said short ply terminates within the completed roll and hence is confined 110 therein by the exterior securing end 5, which secures the convolutions in roll form, but leaves the convolutions free and loose within the outer secured surface.

The inner extremity of the sheet which extends longitudinally and loosely along the bore or center opening of the roll, and of each sheath detached therefrom, is formed by the folded doubled edge 4, whereby certain advantages are attained among other reasons because said doubled edge will not 115 catch on and interfere with the match stem when the sheath is slipped thereon. Each sheath whether torn from an elongated roll, or formed separately, has thin end initial ignition surfaces, for quick almost instant 120 ignition from a burning match head, composed of the edge of the overlying convolutions of the sheet. The combustion of the 125

sheath is accelerated and aided by the fact that the convolutions are thin and comparatively loose and not secured together which also permits or causes the sheath to shrink 5 or contact tightly onto the match stem during combustion. The sheath forms an efficient flare as it will quickly ignite from the burning match head and will then burn and maintain combustion out of doors in wind 10 or strong air drafts.

I do not herein claim the article of manufacture consisting of a series of match flares formed by an elongated tube separable into individual flares as such article is claimed in 15 my application filed March 9, 1909, Se. No. 482315.

It is evident that various modifications and variations in material and formations might be resorted to without departing from 20 the spirit and scope of my invention and hence I do not wish to limit myself to the exact disclosures hereof.

What I claim is;—

1. A tubular match flare composed of a thin tissue-like sheet of combustible material carrying chemical salt to accelerate combustion and rolled on itself into overlying convolutions and secured, whereby the chemical salt is distributed within and throughout 30 the body of said flare and whereby said flare is characterized by contraction of said convolutions on the match stem under combustion, by combustion without extensive flame, and by the production of a live coal residue 35 for ignition purposes.

2. A tubular match flare composed of thin combustible sheet material rolled upon itself into overlying convolutions and impregnated with chemical salt to accelerate combustion without extensive flame and produce a live coal for ignition purposes.

3. A flexible match flare of thin combustible sheet material loosely rolled into overlying convolutions impregnated with chemical salt to accelerate combustion, and characterized by combustion without extensive flame and a live coal residue for ignition purposes.

4. A tubular match flare impregnated throughout with chemical salt to accelerate combustion and composed of thin combustible sheet material rolled on itself into overlying convolutions producing on combustion a live coal residue for ignition purposes.

5. A tubular match flare composed of thin combustible sheet material rolled on itself into overlying convolutions and impregnated with chemical salt to accelerate combustion, said chemical salt being uniformly distributed throughout the body of material forming the flare.

6. A flexible-wall tubular match flare composed of a rolled and pasted tissue-like sheet of combustible material impregnated with chemical salt to accelerate combustion,

said sheet being rolled on itself and secured to form loosely overlying convolutions, said flare having an igniting end formed by the edge of said sheet.

7. A tubular match flare composed of 70 combustible fibrous rolled sheet material impregnated with chemical salt to accelerate combustion, in combination with a match having its stem embraced by said flare and its head partially overlapped by the initial 75 igniting end of said flare formed by the edge of the sheet.

8. A tubular match flare carrying material to accelerate combustion and composed of rolled combustible sheet material, 80 in combination with a match having its stem embraced by said flare and its head cemented to the initial igniting end of said flare.

9. A match flare composed of a combustible sheet rolled on itself and having a rough-edge-igniting end, in combination with a match having its stem embraced by said flare and its head adhering thereto.

10. A rolled sheet of highly combustible 90 material, in combination with a match having its stem inserted through said roll and its head secured thereto by the adhesive quality of the material forming said head.

11. A flare for matches composed of a flexible sheath having initial-igniting overlying end edges, said sheath impregnated with combustible accelerating material and formed by a rolled pasted sheet in combination with a match carrying said flare and 100 having its head adhering thereto.

12. A match flare composed of a tube-like sheath impregnated with material to accelerate combustion, said sheath formed by tissue-like paper rolled into overlying convolutions whereby said convolutions will shrink under combustion and grip the match stem in combination with a match carrying said sheath and secured thereto.

13. A match flare embodying material to accelerate combustion and composed of a tube-like sheath having an initial igniting end edge in combination with a match carrying said flare and having its head cemented thereto by the adhesive quality of the 115 material forming said head.

14. A match flare embodying material to accelerate combustion and composed of thin tissue-like combustible sheet material rolled into overlying convolutions and secured, in combination with a match secured in said flare with its head in quick igniting relation with respect to the initial igniting end of said flare.

15. A match flare consisting of a flexible-wall tube-like paper sheath impregnated with chemical salt to accelerate combustion in combination with a match carrying said flare and having its head partially inclosed 125 thereby.

16. A match flare comprising a sheath carrying material to accelerate combustion and composed of a rolled sheet of thin tissue-like combustible material secured by adhesive containing a chemical salt capable of accelerating combustion.

17. A match flare composed of a thin tissue-like sheet of combustible material impregnated with chemical salt to accelerate combustion and rolled on itself to form a sheath having an end surface of convolution edges for initial igniting.

18. A match flare head consisting of a sheath carrying material to accelerate combustion and adapted to be slipped onto a match stem and ignite from the head thereof and formed of a thin tissue-like sheet of combustible material rolled on itself into overlying convolutions and pasted down, whereby said sheath will shrink on and adhere to the match stem under combustion.

19. A match flare carrying material to accelerate combustion and composed of a folded sheet rolled on itself in overlying convolutions, the fold line of the sheet forming a doubled inner edge within the bore of the flare.

20. A match flare composed of a highly inflammable tube consisting of a folded sheet rolled on itself to form a doubled inner free edge along the bore of the tube and overlying convolutions.

21. A match flare carrying material to accelerate combustion and formed by the loosely overlying inner convolutions of a thin tissue-like sheet of combustible material rolled on itself into tubular form and pasted down at its outer end.

22. A match flare of tubular form and carrying material to accelerate combustion and composed of a sheet of thin tissue-like combustible material rolled on itself into overlying convolutions and pasted down at its outer end only, whereby the inner convolutions loosely overlie.

23. A tubular match flare of highly inflammable material composed of a doubled sheet having a projecting securing end, said sheet rolled on itself to form overlying two ply convolutions and a free doubled inner edge, said securing end being pasted down at the exterior of the flare.

24. A match flare carrying material to accelerate combustion and composed of a thin tissue-like sheet of combustible material rolled on itself in the direction of its length into overlying convolutions and secured at its outer end only to form a match-stem-receiving sheath of loose convolutions.

25. A match flare composed of a sheath carrying material to accelerate combustion and formed by the loosely overlying inner convolutions of a thin tissue-like sheet of combustible material rolled on itself and

pasted down at its outer end at the outer 65 convolution of the sheath.

26. A match flare consisting of a tissue-like rolled sheet having non-secured inner convolutions and impregnated with chemical salt to accelerate combustion whereby 70 said convolutions will shrink under combustion, in combination with a match carrying said flare.

27. A tubular match flare carrying material to accelerate combustion and composed of thin tissue-like combustible sheet material rolled on itself into overlying convolutions and secured with the inner convolutions loose, whereby said flare can be slipped onto a match stem to cause displacement of the loose convolutions by engagement with the match head to permit said flare to lap over said head, substantially as described.

28. A match flare carrying material to accelerate combustion and composed of a sheet rolled on itself to form non-secured inner convolutions, in combination with a match carrying said flare and having its head partially inclosed thereby by the longitudinal 90 displacement of said loose convolutions.

29. A match flare composed of a combustible sheet rolled on itself to form overlying convolutions, the edges of said convolutions forming the igniting end of said flare, in 95 combination with a match having its stem embraced by said flare and its head in contact with said edges.

30. A tubular match flare carrying material to accelerate combustion, in combination with a match having its stem passed through said flare and its head cemented thereto by the adhesive quality of the material forming said head.

31. A sheet of tissue paper, carrying material to accelerate combustion, said sheet rolled on itself into overlying convolutions and pasted to form a tube, in combination with a match embraced by said tube with its head in quick-igniting relation to an end 110 of the tube.

32. A tubular match flare composed of a thin tissue-like sheet of combustible material carrying chemical salt to accelerate combustion and rolled on itself into overlying convolutions and secured whereby said flare is characterized by contraction of said convolutions around the match stem during combustion and the production of a live coal residue adhering to the match stem for ignition purposes in combination with a match carrying and embraced by said flare with the match head in quick igniting relation to the initial igniting end of said flare.

33. A match flare carrying material to accelerate combustion and composed of a thin tissue-like sheet of combustible material rolled on itself into overlying convolutions

in combination with a match having its stem passed through said flare with its head in quick initial igniting relation thereto.

34. A match flare carrying material to accelerate combustion and composed of a thin tissue-like sheet of combustible material rolled on itself in overlying convolutions and secured, in combination with a match having its stem passed through said flare,

10
said match carrying said flare and cemented thereto.

In testimony whereof I affix my signature, in presence of two witnesses.

JOHN DEAN.
